UNITED STATES PATENT OFFICE.

WILLIAM L. WHITE, OF BIRMINGHAM, ALABAMA, ASSIGNOR TO UNDERWOOD TYPE-WRITER COMPANY, OF NEW YORK, N. Y., A CORPORATION OF DELAWARE.

TYPE-WRITER.

1,312,883.

Specification of Letters Patent. Patented Aug. 12, 1919.

Application filed September 24, 1917. Serial No. 194,299.

To all whom it may concern:

Be it known that I, WILLIAM L. WHITE, a citizen of the United States, residing at Birmingham, in the county of Jefferson and State of Alabama, have invented certain new and useful Improvements in Type-Writers, of which the following is a specification.

This invention relates to improvements in typewriting machines, and has for its object to provide an improved column selector and, more particularly, one controlled from the front of the typewriter.

Another object of the invention is to provide means whereby any column on a typewriter in a tabulated form may be instantly selected.

With the above and other objects in view, I have invented the device illustrated in the accompanying drawings in which,

20 Figure 1 is a front elevational view of a typewriter embracing my invention, certain parts essential to the invention being removed;

Fig. 2 is a side elevational view of the machine;

Fig. 3 is a detail elevational view of a typewriter carriage stopping mechanism;

Fig. 4 is a detail plan view of a column selecting means;

30 Fig. 5 is an enlarged detail end view of a portion of the mechanism;

Fig. 6 is a front elevational view of the mechanism shown in Fig. 5; and

Fig. 7 is a detail view of one of the dials and the pointer associated therewith.

Like reference characters indicate like parts throughout the following specification and in the several views of the drawings in which 1 indicates a typewriter frame having

40 a series of dials 2, 3, 4, 5 and 6 positioned at the front of said frame, said dials embracing figures from 1 to 75 conforming to the spaces on the space plate 7 of the typewriter, each dial having fifteen numbers thereon.

45 These dials are read in connection with fixed indicator pointers 8 and are formed on milled heads 9, said heads being fixed to operating shafts 10, 11, 12, 13, and 14, which extend horizontally to the rear portion of

50 the frame and have mounted thereon gears, of which 15, 16 and 19, mounted on shafts 10, 11 and 14, respectively, are shown, meshing with gears fixed to shafts 25, 26, 27, 28 and 29, rotating at right angles to the shafts

55 10 to 14. Of the last-mentioned gears, only

20, 21 and 24 meshing, respectively, with gears 15, 16 and 19 are shown. On the upper ends of shafts 25, 26, 27, 28 and 29 are fixed other gears 30, 31, 32, 33 and 34, which operate gears 35, 36, 37, 38 and 39, fixed on the short shafts 40, 41, 42, 43, 44, respectively. These latter shafts carry pinions 45, 46, 47, 48 and 49 meshing with the racks 50, 51, 52, 53 and 54 on the column selector bars or stops 55, 56, 57, 58 and 59, which are 60 65 66 70 75 80 85 90 95 for preventing such movement, rather than to depend upon the frictional resistance against movement of the bars in their grooves and upon the frictional resistance of the gearing through which said bars are positioned. Such provision is obtained by mounting set screws 2^a, 3^a, 4^a, 5^a, and 6^a in the frame of the machine so that they can be turned to clamp, against improper movement, the shafts, carrying the milled heads 9, and thereby prevent improper displacement of said column-selecting bars 55 to 59, inclusive.

When it is desired to set a column-selecting bar to correspond with a certain indication on the space plate 7, the milled head, having on its face an indication corresponding to the one selected on the space plate, is turned until the indication lies under the fixed pointer associated with said milled head. Then, upon depression of the proper spring-controlled pin carried by plate 66 in response to actuation of the associated key, the carriage when released will be stopped at the desired position. It will be understood that with each milled head set at its lowest indication, the corresponding column-selecting bars will be positioned at the lower limit of the range controlled thereby, and turning of any of said milled heads in a clockwise direction will cause a higher space number to be indicated, and will at the same time move the corresponding bar to the left.

35 Variations may be resorted to within the scope of the invention, and portions of the improvements may be used without others.

Having thus described my invention, that which is claimed as new and desired to be

40 secured by Letters Patent is:

1. In a typewriting machine, the combination with a traveling carriage, of column-selecting means including stops mounted at the rear of the machine, each adjustable transversely of the machine, means for severally setting said stops in adjusted position, said setting means including devices through which actuation of said setting means is effected, positioned at the front of the machine and having thereon scales numbered to conform with the numbering on the space scale of the machine, and indicators associated with said scales, whereby the positions of said stops relative to the space scale will be indicated, and means on said carriage for engaging with said stops.

2. In a typewriting machine, the combination with a traveling carriage, of column-selecting means therefor comprising a stop mounted at the rear of the machine and settable along a line parallel to the path of movement of said carriage, means for setting said stop at a desired position along said path of movement, and means, mounted at the front of the machine and associated

with said setting means, for indicating the position of said stop with reference to the space scale of the machine, said indicating means including a scale having figures thereon conforming to the figures on said space scale, and an indicator associated therewith.

3. In a typewriting machine, the combination with a traveling carriage, of a series of stops therefor, and means for moving each of said stops transversely of the machine, said stop-moving means including actuating members mounted at the front of the machine and having associated therewith dials and indicators to show the positions of said stops, said dials having figures thereon conforming to the figures on the space scale of said machine.

4. In a typewriting machine, the combination with a traveling carriage, of a series of stopping devices therefor, means for severally setting said stopping devices, tabulator keys, and tabulator-key-actuated means, connected to said carriage to move therewith, for determining which of said stopping devices shall be rendered effective.

5. In a typewriting machine, the combination with a carriage, of a column-selector including a series of stops severally adjustable along limited ranges to correspond to certain positions on the space scale of the machine, means for adjustably setting said stops, a second series of stops, and means including keys to severally place the stops of said second series in position to engage the corresponding stops of the first series, the stops of the second series determining the ranges, and the stops of the first series determining the points in said ranges at which the carriage is to be stopped.

6. In a typewriting machine, the combination with a carriage, of tabulating means including slidable stop bars having racks thereon, a plurality of dial members rotatably mounted at the front of the machine, said dial members having figures thereon conforming to the figures on the space scale of said machine, an indicator associated with each of said dial members, and connections between said dial members and said slidable stop bars including shafts carrying pinions geared with said racks, whereby setting of said dial members for certain readings will set the slidable stop bars in corresponding positions.

7. In a typewriting machine, the combination with a traveling carriage, of stops therefor, stop-supporting means at the rear of the machine permitting adjustment of each of said stops along the path of travel of said carriage, and means for severally positioning said stops along said path of travel, said positioning means including devices located at the front of the machine by means of which said positioning means can be actuated.

8. In a typewriting machine, the combination with a traveling carriage, of tabulating mechanism including stops slideable transversely of the machine and mounted on the 5 frame at the rear thereof, means for severally positioning said stops, a second series of stops mounted in a frame connected to travel with said carriage, each stop of said second series being supported so that it can 10 be positioned to engage the corresponding stop of the first set but being held normally retracted, and key-actuated means to project a selected stop of the second series into position to engage the corresponding stop of 15 the first series during the travel of the carriage, and thereby position said carriage as desired.

9. In a typewriting machine, the combination with a traveling carriage, of a series of 20 stops vertically offset with respect to each other and supported so as to permit adjustment along the path of carriage movement, means for adjusting said stops along said path of movement, a second series of stops 25 mounted to move with said carriage and placed so that each of them lies in horizontal alinement with a stop of the first series, means for holding the stops of said second series in retracted position to prevent engagement thereof with stops of the first 30 series, and means to selectively project stops of said second series and thereby position said carriage by engagement of the projected stop with the corresponding stop of 35 the first series.

10. In a typewriting machine, the combination with a traveling carriage, of a series of stops vertically displaced with respect to each other and mounted on the 40 frame at the rear of the machine, a second series of stops slideably supported in a frame connected to travel with said carriage, each stop of said second series being in horizontal alinement with a stop of the first series, 45 spring means for pressing the stops of the second series toward the front of the machine and thereby preventing engagement between stops of the two series, means for operatively positioning stops of the second 50 series including a bell crank for each stop, and a pivoted plate co-extensive with the writing range of said carriage interposed

between each of said bell cranks and the corresponding stop, thereby maintaining operative connection between said bell crank 55 and the corresponding stop throughout the travel of the carriage.

11. In a typewriting machine, the combination with a traveling carriage, of denominational stops adjustable transversely 60 of the machine, means to position said denominational stops in adjusted position, column stops mounted to move with the carriage, means for holding said column stops normally in retracted position to prevent 65 engagement thereof with the denominational stops, said denominational stops and said column stops being so supported that a column stop when projected can engage only the corresponding denominational stop, 70 and means to selectively project said column stops into position to engage the denominational stops, and thereby determine the positions at which the carriage will be stopped.

12. In a typewriting machine, the combination with a traveling carriage, of a column-selecting device including a plurality of rotatable heads mounted at the front of the machine, each of said heads having associated therewith a dial having 80 figures thereon conforming to the figures on the space scale of said machine, and an indicator for said dial, a plurality of stop bars slidably mounted in grooves in a plate supported on the frame, connections whereby each of said stop bars will be actuated by means of the corresponding rotatable head, said connections including a rack on each of said stop bars and a pinion meshing therewith, a plurality of spring-retracted pins 90 mounted on said carriage in alinement with said grooves, and means for selectively projecting said pins into the corresponding grooves and thereby causing the movement of the carriage to be checked by engagement 95 of a projected pin with the corresponding stop bar.

In testimony whereof I affix my signature in the presence of two witnesses.

WILLIAM L. WHITE.
